UNITED STATES PATENT OFFICE.

FRANK E. SOUTHARD, OF TOLEDO, OHIO, ASSIGNOR TO THE TOLEDO METAL WHEEL COMPANY, OF TOLEDO, OHIO, A CORPORATION OF OHIO.

DESIGN FOR A JUVENILE VEHICLE-BODY.

52,547.

Specification for Design.

Patented Oct. 8, 1918.

Application filed July 13, 1917. Serial No. 180,452. Term of patent 14 years.

To all whom it may concern:

Be it known that I, FRANK E. SOUTHARD, a citizen of the United States, residing at Toledo, in the county of Lucas and State of Ohio, have invented a new, original, and ornamental Design for a Juvenile Vehicle-Body, of which the following is a specification, reference being had to the accompanying drawings, forming a part thereof.

The figure is a perspective view of a juvenile vehicle body showing my new design.

I claim:

The ornamental design for a juvenile vehicle body substantially as shown.

FRANK E. SOUTHARD.
